(57) **CLAIM**

The ornamental design for an actuator overcap for an aerosol container, as shown and described.

DESCRIPTION

FIG. 1 is a perspective view of an actuator overcap for an aerosol container showing our new design;

FIG. 2 is a top plan view thereof;

FIG. 3 is a right side elevational view thereof with the left side elevational view being a mirror image thereof;

FIG. 4 is a front elevational view thereof;

FIG. 5 is a rear elevational view thereof; and,

FIG. 6 is a bottom plan view thereof.

The broken lines in FIGS. 1, 2, 4, 5 and 6 are for illustrative purposes only and forms no part of the claimed design.
